J. KLEPACH

GRAVEL CLEANER

Filed Dec. 7, 1922

*Inventor
John Klepach
by J. M. & John
Atty.*

UNITED STATES PATENT OFFICE.

JOHN KLEPACH, OF CEDAR RAPIDS, IOWA.

GRAVEL CLEANER.

Application filed December 7, 1922. Serial No. 605,497.

To all whom it may concern:

Be it known that I, JOHN KLEPACH, a citizen of the United States, residing at Cedar Rapids, in the county of Linn and 5 State of Iowa, have invented certain new and useful Improvements in Gravel Cleaners; and I do hereby declare the following to be a full, clear, and exact description of the invention, such as will enable others 10 skilled in the art to which it appertains to make and use the same.

This invention relates to the preparation of sand and gravel for use in building operations, more particularly the making of 15 concrete, the object of the invention being to rid such sand or gravel of refuse matter such as would render it unfit for use for the purposes indicated.

It is to be understood that the best plaster sand is generally taken from river beds, and the same would be true of gravel, if it 20 were not for the common mixing in its natural condition of the gravel with much refuse stuff—mud, leaves, sticks and general débris, waterlogged, and so commingled with the gravel as to be unsiftable therefrom. This invention provides simple apparatus by means of which the gravel is 25 cleansed as it is excavated, and at practically no expense.

The invention is fully set forth in the description and claims following, reference being had to the accompanying drawing, in which:—

35 Fig. 1 is a view in perspective illustrating a simple embodiment of the invention. Fig. 2 is an end view of the separator, looking toward the upper end.

In the drawing, the numeral 5 denotes 40 the discharge end of a delivery pipe or trough through which the material is forced by a sand-pump (not shown), taking the same from a river bed or pit. The solid matter, with a large admixture of water, 45 forms a semi-fluid mass, which flows somewhat freely at a practical level. The invention takes advantage of this characteristic, in the following manner.

On suitable supports 6 is mounted, by its 50 bearings 7, a rotary sluice-box 8, the farther end of which extends under the discharge pipe or trough above mentioned. The sluice-box is composed of a large, square axle portion 9, provided with end gudgeons

10 as bearings. The axle is most conveniently formed of wood, the bearings being enclosed in steel rings 11. To this axle are attached radial wings 12, provided at the outer sides with side-boards 13 standing at right angles to the the wings. End-boards 14 retain the material at the receiving end, as shown. By reference to Fig. 2 it will be seen that a considerable portion of each sluice-box is bottomed on the axle, and the box may thus hold quite a load of material 15 before the weight thereof, spreading laterally, becomes sufficient to rotate the structure as a whole, and thus dump the collected load. This it does automatically, the succeeding wing serving as a new sluice-box. 20

The cleansing of the gravel 15 is also performed automatically, and by the simple flowage of water. The extended sluice-box affords room for the gravel to settle by 25 gravity, and the lighter, refuse material is 30 carried forward over the foot of the sluice-box, past the gravel, whether in the box or dumped, and is thus so effectually separated from the gravel that the latter, well 35 cleansed, may be shoveled up for constructional use. 40

I claim:

1. Gravel-cleaning apparatus, comprising, 45 in combination with means for producing a flow of gravel and water, a sluice-box elongated in the direction of said flow, and pivoted to tip laterally, and partly below the bottom of the box, whereby the box may 50 accumulate a load, but dump by gravity, the refuse being carried over the end of the 55 box and past the cleansed gravel. 60

2. Gravel-cleaning apparatus, comprising, 65 with means for producing a flow of gravel and water, a rotary sluice-box comprising a central axle and lateral gravel-holding 70 wings, partly projecting inside the center of gravity, whereby the deposited gravel, cleaned by the endwise flow of water, is automatically dumped back of the flow of refuse 75 by the partial rotation of the sluice-box 80 when the weight of the load falls outside the center of gravity. 85

In testimony whereof I affix my signature in presence of two witnesses.

JOHN KLEPACH.

Witnesses:

H. WALTER TAYLOR,
ERNEST MELBERG.
